CHILD'S SHOE TREE

Dorothy Compton Wearing, Chicago, Ill.

Application August 13, 1949, Serial No. 4,488

Term of patent 14 years

(Cl. D7—3)

To all whom it may concern:

Be it known that I, Dorothy Compton Wearing, a citizen of the United States, residing at Chicago, Cook County, Illinois, have invented a new, original, and ornamental Design for Child's Shoe Tree, of which the following is a specification, reference being had to the accompanying drawing, forming a part hereof.

The figure is a perspective view of a child's shoe tree showing my new design, the opposite side presenting generally the same appearance as the side shown except for the region of the instep, which is shaped to conform to the instep of a child's foot.

I claim:

The ornamental design for a child's shoe tree, substantially as shown and described.

DOROTHY COMPTON WEARING.
